HAIR BRUSH

William Hertzberg, New York, N. Y., assigner to
Hertzberg Patents, Inc., New York, N. Y., a
corporation of New York

Application May 26, 1939, Serial No. 275,814

2 Claims. (Cl. 15—206)

This invention relates to brushes and more particularly to hair brushes in which the brush part is renewable and in which the bristles may easily and conveniently be cleaned.

5 It is an object of this invention to provide a brush which has the above advantages and is rigid and simple in construction and which may easily be taken apart for cleaning and in which the bristles may be renewed when worn out by 10 replacing one or the other worn brush.

With these and other objects in view which will appear more clearly as the description proceeds, the invention consists in the novel construction, adaptation and arrangement of parts 15 hereinafter described and illustrated in the accompanying drawing, in which—

Fig. 1 is a perspective view of my new hair brush.

Fig. 2 is a side elevation of the brush.

20 Fig. 3 is a sectional elevation on the plane of the line 3—3 of Fig. 2.

Fig. 4 is a sectional elevation on the plane of the line 4—4 of Fig. 2.

Fig. 5 is a sectional elevation on the plane of the line 5—5 of Fig. 2.

Fig. 6 is a view of one of the removable brushes.

Referring to the drawing, a brush handle 10 is provided with a plate 11 preferably integral therewith and forming an elongation of the 30 handle and parallel to the handle-axis and offset thereto by means of a transverse plate 12. A similar transverse plate 13 forms the end of the brush opposite the handle 10.

The handle 10 with plates 11, 12 and 13 is preferably made of aluminum, plastic moldable compound, wood or other suitable material. The bristles forming the brush are preferably entwisted between three separate pairs of metallic wires which form the stems for the cylindrical brushes 14, 15 and 16, which protrude at either end of the brushes for a short distance 14a, 15a and 16a as shown in Fig. 6. The ends 12x, 13x and 14x of the three cylindrical brushes are mounted in cylindrical apertures on the inside face of plate 12 (see Fig. 5). The opposite ends of stems 14e, 15e and 16e are inserted into corresponding oppositely located circular apertures in the inside face of transverse plate 13 by sliding

them when the stem is slightly shortened in length (by bending it as shown in Fig. 1) through the horizontal groove 13a and vertical groove 13b into aperture 13ba, and in a similar manner the stem 15e with brush 15 is inserted through 5 grooves 13a and 13c into aperture 13ca, the last brush stem end 16e of course being inserted in the same manner into aperture 13da. When the stem ends have reached their final positions opposite their respective apertures in plate 13 the pressure 10 for bending them is released and they slide a short distance into these apertures locking the brush in the desired position.

In this simple manner a very useful hair brush which can be made and sold for a very reasonable price has been made and is offered to the public.

It is of course possible to make changes in the details of construction without departing from the invention and I therefore desire to be limited 20 only by the state of the prior art and the appended claims.

I claim:

1. A hair brush forming a curved brushing surface consisting of a plurality of cylindrical 25 brushes each brush having a stem consisting of a pair of resilient metallic wires and bristles entwisted therebetween, the stems of said brushes being arranged in triangular formation parallel to an elongated plate having transverse ledges 30 at its ends with an entrance slot in one ledge and oppositely aligned apertures on the inside of said ledges holding the ends of said stems so that the outline of the bristles thereon forms a curved 35 surface.

2. A hair brush comprising a concavo-convexo shaped back portion, an inwardly extending ledge portion at each end of the back portion, each ledge portion being formed with openings in opposed relationship to the other ledge and one of 40 said ledges being formed with a transverse slot communicating with its respective openings, a plurality of brush members detachably supported between said ledges, each brush member including a wire stem with its ends in said opposed 45 openings and bristles on the wire stem.

WILLIAM HERTZBERG.
